GLOW-DISCHARGE TUBE

Simon Mari Frouws, Eindhoven, Netherlands, assignor to North American Philips Company, Inc., New York, N.Y., a corporation of Delaware

Application June 10, 1957, Serial No. 664,751

Claims priority, application Netherlands June 22, 1956

1 Claim. (Cl. 313—197)

This invention relates to glow-discharge tubes in which an auxiliary anode is located near the main cathode and the main electrodes are parallel flat plates.

In known tubes, the anode is often wire-shaped in order to increase the break-down voltage. The auxiliary anode also is often shaped as a wire so that the ignition voltage of the auxiliary anode is comparatively high even in the case of an optimum electrode distance. Furthermore, oscillations often occur when using filamentary anodes and high ignition voltages. However, oscillations also occur due to the usual gas mixtures which are so chosen as to decrease the auxiliary anode ignition voltage. As a rule, the properties of these mixtures are relatively insensitive to impurities.

These tubes often involve a problem in that a high ratio is required between the ignition voltage of the main anode and that of the auxiliary anode and in spite thereof no oscillation must occur during the main discharge.

According to the invention, in a glow-discharge tube having an auxiliary anode arranged near the main cathode and in which the main electrodes are parallel flat plates, the gas-filling consists of a pure rare gas having such a pressure that the product of this pressure and the distance between the main electrodes lies to the right of the minimum of the Paschen curve of the gas concerned, but is smaller than the value at which oscillations occur, while the auxiliary anode is a flat element which is situated near a sharp projecting part of the main cathode so that the break-down voltage of the auxiliary anode is lower than that corresponding to the minimum of the Paschen curve. However, this projecting part is situated laterally of the main discharge path so that the breakdown voltage is not reduced by it.

According to the invention, in connection with the comparatively short distance from the main anode, the auxiliary anode consists of a material having a work function in excess of that of the cathode in order that the breakdown voltage from the main anode to the auxiliary anode shall be sufficiently high. This is of importance for those circuit arrangements in which the auxiliary anode may assume cathode potential. Tubes according to the invention have the advantage that no oscillation occurs in spite of the high anode ignition voltage, as a result of the electrode arrangement and the gas filling. Flat anodes give less rise to oscillations than wire-shaped anodes because the last easily introduce an anode fall also so-called Penning mixtures are more subject to oscillations. Notwithstanding that, the auxiliary anode ignition voltage is low because the auxiliary anode faces a sharp part of the cathode. As a result of the pure gas the de-ionization time is short.

2

In order that the invention may be readily carried into effect, an example will now be described in detail with reference to the accompanying drawing, in which Fig. 1 is a vertical cross-section and Fig. 2 is a cross-section of the device shown in Fig. 1 the section being taken along the line II—II.

A number of lead-through conductors carrying the electrode system are sealed into the bottom 1 of a glass bulb. The main cathode is a molybdenum slab 3 having a rounded edge. The main anode is a flat molybdenum disc 4. A narrow molybdenum strip 5 forming one piece with the cathode is bent out of the plane of the cathode and is closely spaced apart from an auxiliary anode 6 in the form of a flat nickel strip projects from the cathode laterally of the main discharge path. Behind the main anode is provided an auxiliary cathode 7 which carries a very weak current during operation of the tube, in order to avoid ignition delays. The supply conductors for the auxiliary anode and the main cathode are surrounded by tubes in order to prevent short-circuits due to layers of material disintegrated on the wall, and for shielding the cathode supply conductor from the anode. The main-electrode spacing is 3 mms. and the gas-filling consists of pure neon at a pressure of 50 mms. The spacing between the auxiliary anode 6 and the strip 5 bent out of the cathode is 0.25 ± 0.10 mm. The spacing between anode 4 and auxiliary anode 6 is 2.4 mm. The breakdown voltage between the main electrodes is 340 volts, that from the auxiliary anode to the main cathode is 145 volts. It is to be noted that for pure neon and molybdenum as a cathode the minimum breakdown voltage occurs at a product of distance times pressure of $p_0 d = 2$ mm. cm. with a value of 155 volts. In the present case the $p_0 d$ is 27 mm. $\times$ cm. between the main electrodes.

35 What is claimed is:

A glow-discharge tube comprising an envelope; spaced, parallel, substantially planar main anode and cathode electrodes disposed within said envelope and defining a main discharge path therebetween, said cathode having a projecting portion extending outwardly from the plane of the flat portion thereof; a filling of pure neon in said envelope at a pressure at which the product of the distance between the main electrodes and the gas-pressure lies to the right of the minimum of the Paschen curve of said gas but smaller than that at which an oscillation in the gas occurs; a planar auxiliary anode spaced from a projection of the main cathode defining an auxiliary discharge path located laterally from the main discharge path in order not to reduce the breakdown potential of the latter, said auxiliary anode being spaced from said projection of said main cathode a distance at which the breakdown potential of the auxiliary discharge path is lower than that corresponding to the minimum of the Paschen curve of the gas; and an auxiliary cathode spaced 55 from said main anode to initiate the discharge between said main electrodes.
